(57) **CLAIM**

The ornamental design for a tool and part holder, as shown and described.

DESCRIPTION

FIG. 1 is a front elevational view of a tool and part holder showing our new design, the rear elevational view being a mirror image thereof;

FIG. 2 is a right side elevational view of FIG. 1;

FIG. 3 is a left side elevational view of FIG. 1;

FIG. 4 is a top plan view of FIG. 1; and,

FIG. 5 is a bottom plan view of FIG. 1.
